(57) **CLAIM**

The ornamental design for an electronic gaming machine wheel topper, as shown and described.

DESCRIPTION

FIG. 1 is a perspective view of a first embodiment of an electronic gaming machine wheel topper showing our new design;

FIG. 2 is a perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side view thereof;

FIG. 8 is a left side view thereof;

FIG. 9 is a perspective view of a second embodiment of an electronic gaming machine wheel topper showing our new design;

FIG. 10 is a perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a right side view thereof;

FIG. 16 is a left side view of;

FIG. 17 is a perspective view of a third embodiment of an electronic gaming machine wheel topper showing our new design;

FIG. 18 is a perspective view thereof;

FIG. 19 is a front elevational view thereof;

FIG. 20 is a rear elevational view thereof;

FIG. 21 is a top plan view thereof;

FIG. 22 is a bottom plan view thereof;

FIG. 23 is a right side view thereof;

FIG. 24 is a left side view thereof;

FIG. 25 is a perspective view of a fourth embodiment of an electronic gaming machine wheel topper showing our new design;

FIG. 26 is a perspective view thereof;

FIG. 27 is a front elevational view thereof;

FIG. 28 is a rear elevational view thereof;

FIG. 29 is a top plan view thereof;

FIG. 30 is a bottom plan view thereof;

FIG. 31 is a right side view thereof; and,

FIG. 32 is a left side view thereof.

In the drawings, the broken lines depict environmental subject matter only and form no part of the claimed design.
